A. STEPHEN,

APPARATUS FOR TREATING ARTICLES OF PAPER, CARDBOARD, AND THE LIKE WITH
WATERPROOFING MATERIAL.
APPLICATION FILED JAN. 9, 1913.

UNITED STATES PATENT OFFICE.

ALEXANDER STEPHEN, OF LONDON, ENGLAND.

APPARATUS FOR TREATING ARTICLES OF PAPER, CARDBOARD, AND THE LIKE WITH WATERPROOFING MATERIAL.

1,140,626.

Specification of Letters Patent.

Patented May 25, 1915.

Application filed January 9, 1913. Serial No. 740,944.

To all whom it may concern:

Be it known that I, ALEXANDER STEPHEN, a subject of the King of Great Britain, residing at London, England, have invented a new and useful Improved Apparatus for Treating Articles of Paper, Cardboard, and the like with Waterproofing Material, of which the following is a specification.

This invention relates to an improved apparatus for use in impregnating articles of paper, cardboard, and the like, after having been made up into boxes, or other receptacles, with wax or other similar material or compound which is capable of being liquefied by the application of heat.

My approved apparatus consists of (a) a vessel in which the impregnating material or compound is maintained in a liquefied condition at a temperature of from 120 to 200 degrees Fahrenheit, and into which the articles to be treated are dipped or plunged; (b) an impregnating and draining chamber of special shape heated to a temperature of from 140 to 240 degrees Fahrenheit, through which the articles are caused to travel as the impregnation is completed in a thorough manner, and the superfluous impregnating material is removed; and (c) a traversing surface which receives the articles as they leave the impregnating and draining chamber, and upon which they are retained until the impregnating material or compound has completely set. The temperatures of the impregnating material or compound and of the impregnating and draining chamber may be varied according to the impregnating material or compound employed, and according to the desired quality and finish of the articles treated.

40 The accompanying drawing illustrates diagrammatically apparatus constructed according to my invention, Figure 1 being a side elevation, and Fig. 2 a transverse section on line X—X of Fig. 1.

45 The vessel in which the impregnating material or compound is melted and maintained at the required temperature consists of a bath or copper *d* furnished with a jacket *e* in which air is circulated and heated by a gas ring or other suitable burner *f*, the heat from which may be directed by any convenient form or arrangement of baffle plates. A second jacket *g* preferably embraces the first jacket *e* and contains asbestos or other 55 non-conducting material to prevent the

wasteful radiation of heat. The bath or copper *d* containing the impregnating material or compound *h* is situated preferably at one end of the impregnating and draining chamber *i* as shown in Fig. 1. This chamber *i* may be constructed of sheet iron and of any suitable length. It is open at each end, but doors *j* and *k* are provided at the lowest part thereof which may be kept closed when it is desired to raise the temperature of the 65 interior, or when the apparatus is not in use. The chamber *i* is fitted with an endless traversing surface which may conveniently consist of a series of endless brass chains *m* running in grooves *n* in rotating rollers *o* which 70 may be driven by gearing or belts outside the chamber *i* in any suitable or convenient manner. One of these rollers *o* may be situated near the bottom or floor of the chamber *i* at each end thereof, and two others at 75 a convenient distance apart and from the roof *p* of the central portion of the said chamber, as shown in the drawing, in such a manner that when the articles under treatment are removed from the bath or copper 80 *d* they may be laid on the chains *m* at the inlet end of the chamber *i* and be carried in an upwardly inclined direction to the upper central part thereof, then in a more or less horizontal direction through such upper central part, and down a second incline to the outlet end of the chamber as indicated by arrows in Fig. 1. When they reach the outlet end of the chamber *i*, they leave the chains *m*, and are automatically received by 85 another endless traversing surface which may conveniently consist of a series of endless brass chains *q* running over grooved rollers *r* as before, which convey the impregnated articles in a horizontal direction for a 90 convenient space in the open air, where the articles are cooled and the impregnating material is completely set. This cooling may be accelerated by the employment of rotary or other fans, or in some cases the articles 95 may be passed through a second chamber where they are chilled in any convenient known manner. The chains *m* and *q* may be provided with projections at convenient distances apart in order to insure the forward travel of the articles under treatment.

The floor of the impregnating and draining chamber *i* forms a tray *s* which is preferably inclined toward the copper *d*, ter. 110

minating in a spout *t*. The tray *s* is provided with a jacket *u* through which heated air is circulated. For this purpose the jacket *u* may be connected by any convenient number of pipes or conduits *v* with the heated air jacket *e* of the copper *d*, and also with the uptakes *w* of gas or other suitable burners *x* contained within the hoods or casings *y* which are situated underneath the chamber *i*. The jacket *u* of the tray *s* may be connected at the outlet end of the chamber *i* with the interior of the said chamber, or by other suitable pipes or conduits with the heated air jacket *e* of the bath or copper *d*, in such a manner as to insure an inclosed or continuous circulation of heated air. The interior of the chamber *i* may be also further heated by the admission of heated air directly from the jacket *e* of the copper *d* by means of the pipes such as shown at *z* for example in Fig. 1, and also from the hoods or casings *y* of the burners *x* by means of the uptakes *w*.

The exterior surfaces of the chamber *i* are preferably coated or clothed with asbestos or other suitable non-conducting material for maintaining a regular and high temperature within the said chamber, and inspection doors, such as shown for example at 3 in Fig. 1, may be provided in the walls or roof of the chamber at convenient positions.

The chamber *i* may be supported by frames 4. After the chamber *i* and the contents of the bath or copper *d* have been raised to the necessary temperature, the articles to be treated are first dipped or plunged into the heated liquid contents of the bath or copper *d*, and are then lifted out and placed on the endless chains *m* at the entrance of the chamber *i*. As they are raised by the said chains toward the upper central part of the chamber *i*, and travel along the same, and down to the outlet end, the heated condition of the chamber causes thorough impregnation to take place, and also

causes any superfluous impregnating material to drain off and fall on to the tray *s*, which being suitably inclined toward the copper *d*, returns the said superfluous material thereinto to be used again. 50

The object of making the chamber *i* of the shape described and shewn, is to provide above the horizontal space immediately between the entry and exit openings at *j* and *k* an upper space which forms a pocket in which the heated air accumulates, and is, comparatively speaking, unaffected by the cooling of the lower stratum of air due to the necessity of the doors *j* and *k* being open 60 during the impregnating and draining process. By this arrangement of chamber a much more thorough impregnation and perfect draining is effected as all objectionable cooling or chilling of the articles is avoided. 65

Claim.

An apparatus for treating articles of paper, cardboard and the like with waterproofing material comprising the combination with an impregnating and drying chamber, 70 a hot air pocket in the upper part of said chamber and inlet and outlet openings in the end walls thereof of a conveyer adapted to receive the articles to be treated at the inlet opening and convey same in an upward 75 direction to the top of said pocket, then in a horizontal path along the upper part of said pocket and finally in a downward direction to said outlet opening, a trough for receiving the superfluous waterproofing 80 material while the articles are so conveyed and returning the same to the vessel containing the waterproofing material and means for heating said trough and said vessel, substantially as specified. 85

In testimony whereof I have signed my name to this specification in the presence of two subscribing witnesses.

ALEXANDER STEPHEN.
